[57] CLAIM

The ornamental design for a soft sculpture, as shown and described.

DESCRIPTION

FIG. 1 is a front elevational view of a soft sculpture
showing my new design;

FIG. 2 is a bottom plan view thereof;

FIG. 3 is a right side elevational view thereof;

FIG. 4 is a left side elevational view thereof; and

FIG. 5 is a top plan view thereof.

The strands are shaded to indicate color and shown broken away in FIGS. 3 and 4 for ease of illustration.

FIG. 5

FIG. 4
